UNITED STATES PATENT OFFICE.

MARTIN ALBRECHT, OF FRIEDBERG, GERMANY, ASSIGNOR TO FELTEN & GUILLEAUME-LAHMEYERWERKE ACTIEN-GESELLSCHAFT, OF FRANKFORT-ON-THE-MAIN, GERMANY.

DYNAMO-ELECTRIC VARIABLE-SPEED AND REVERSING GEARING.

No. 861,931.

Specification of Letters Patent.

Patented July 30, 1907.

Application filed February 13, 1907. Serial No. 357,208.

To all whom it may concern:

Be it known that I, MARTIN ALBRECHT, a subject of the German Emperor, and a resident of Friedberg, Grand Duchy of Hesse, Germany, have invented certain new and useful Improvements in Dynamo-Electric Variable-Speed and Reversing Gearings, of which the following is a specification.

This invention relates to improvements in dynamo-electric variable speed and reversing gearings; and the object of the improvements is to provide an apparatus of this class by which the speed of a constantly rotating prime mover may be transmitted to two separately driven wheels at any desired ratio without the use of a differential gearing for varying the ratio of the transmission. And for this purpose the improved apparatus consists of a dynamo-electric gear and an electrically coupled motor, both of which separately drive a carriage wheel. A carriage provided with the apparatus can be reversed, though a special reversing gearing is not provided, because the momentum of the motor can be increased relatively to that of the dynamo electric gear, and the motor can be reversed by changing the direction of the current. The speed is varied by regulating the magnetic field of the motor.

For the purpose of illustrating the invention, several examples of the apparatus are shown in the accompanying drawings, in which—

Figure 1 is a plan-view, partly in section, of an example of the apparatus, and Fig. 2 is a similar view of a modification of the same, showing, as an example of means to balance the motor, an auxiliary dynamo the field winding of which is connected with the armature winding of the motor, and which is operated by the prime mover, Fig. 3 is a similar view of a further example of balancing means, consisting in a fan operated by the dynamo, and an auxiliary dynamo independent of the motor and main dynamo, and operated by the prime mover, the current of which is supplied to the motor, Fig. 4 is a similar view of a further example in which the power is balanced by means of a fan connected to the dynamo, and Fig. 5 is a similar view showing a modification of the dynamo electric gear.

Similar letters of reference refer to similar parts throughout the views.

To a shaft 1 (Fig. 1) power is transmitted from any desired source, so that the armature 2 (or, in some cases, the field magnets 8, 8), of a dynamo is continuously rotated. By such rotation of the armature relatively to the field magnets an electric current is produced in the winding of the latter, which, by collectors 3, 4 and 5, is collected, and conducted to an electro-motor consisting of an armature 6 and field magnets 7, 7. The field-magnets 8, 8 of the dynamo are mounted on a rotary shaft 9. They are therefore rotated according to

the electric energy produced in the armature, and transmit such rotation to the shaft 9, from which further transmission of power may be effected by means of a toothed gearing, chain and sprocket wheel, belt gearing, or the like. The electro-motor rotates a shaft 10, from which power may be transmitted by means of a toothed gearing, chain and sprocket wheel, or belt gearing.

The electric gear and the electromotor may be inclosed within a casing 11 supporting the shaft bearings.

Referring to Fig. 1, it will be seen that the left hand brushes of the armatures 2, 6, are directly connected and that one terminal of the field 7 is connected with the right hand brush of armature 6, and the other terminal of said field 7 is connected with one terminal of the field 8, the other terminal of the latter being connected to the right hand brush of the armature 2. The resistances 12, 13 are respectively connected across the fields 8, 7. The circuit thus formed extends from the left hand brush of armature 2 through armature 6, fields 7, 8, and to the right hand brush of armature 2, the strength of the fields depending upon the position of the movable arm coacting with the resistances 13, 12. The field of the magnets 7 and 8 can be regulated by means of rheostats 12 and 13 respectively. Different types of electrical machines may be used for the dynamo and for the motor. The windings of the field magnets may be energized by a source of electricity provided outside the dynamo, or they may be wound in series, in shunt, or in compound to the armatures, or the dynamo and the motor may be substituted by single or polyphase alternating current machines.

In the apparatus shown in Fig. 1, the power transmitted to each of the wheels is different, whereby the steering mechanism is constantly affected. This influence on the steering mechanism is the more detrimental, the more the speed of the vehicle is increased. To avoid this disadvantage, the arrangement shown in Fig. 2 is designed, in which the field winding 14 of a small auxiliary dynamo is connected with the windings of the fields 7, 8, the armature 15 of said auxiliary dynamo being directly rotated by the driving means while the field magnets are mounted on the motor shaft 10. The current produced by this additional dynamo is used to energize the magnet fields 8, 8 and 7, 7 of the electric gear and the electromotor. By the reaction of the magnet field 14 and the armature 15 of the additional dynamo the torque exerted on the shaft 10 by the electro-motor 6, 7 is increased. The current of the field magnet winding is regulated by switching in resistances.

It will be seen that the armatures 2, 6 are included in a circuit containing suitable resistance, the fields 7, 8 are included in a circuit containing resistance, and

having a connection with the armature circuit, and that the fields and armatures of the auxiliary dynamo are arranged in a circuit including the fields 7, 8. By this means said auxiliary dynamo acts to energize the fields 7, 8, the circuit from each of said fields leading from the left hand terminal of the field 14 to the left hand terminals of the fields 7, 8, and the right hand terminals of each of said fields being connected through suitable resistance with the left hand brush of the armature 15, the right hand brush of which is connected with the right hand terminal of the field 14.

It is apparent, that, instead of the armature, the magnet field of the additional dynamo may be rotated, 15 in which case the torque exerted by the motor would be increased by the reaction of the armature.

An example of the relation of the dynamo and the motor will explain the effect of the additional motor. If the difference of the power of the dynamo electric 20 gear and the electromotor be 30 per cent., 10 per cent. of the same will be used for energizing the magnet poles. These 10 per cent., however, will be added to the effect of the electromotor, on account of the reaction of the armature and magnet pole of the additional 25 dynamo, so that the difference of the main dynamo and the electromotor is decreased to $30 - 2 \cdot 10 = 10$ per cent. The remaining difference can be balanced by causing the additional dynamo to produce a little more current, than what is required to set up the magnetic fields, 30 which current may be used to charge a little battery, from which current may be supplied for the purpose of starting the motor, for lighting purposes, or the like. A further example, how the difference of the power 35 may be balanced, is shown in Fig. 3. It consists in connecting a fan to the part of the dynamo coupled to the carriage wheel, and in increasing the torque of the electromotor by means of an auxiliary dynamo driven by the main driving shaft, the current produced being supplied to the electromotor.

40 From the driven element, and, in the example shown, from the magnet poles 8, 8 of the dynamo, motion is imparted to a fan 16 rigidly connected therewith and to the carriage wheel connected with the fan by a toothed gearing, a chain and sprocket wheel or the like. The current produced in the armature 2 is supplied, as in the examples shown in Figs. 1 and 2, to the motor 6, 7. The magnet poles of the latter are stationary, and its armature transmits its energy to the wheel connected therewith. The auxiliary dynamo 45 14, 15, provided for to increase the torque of the motor, is rotated by the main driving shaft 1, just as the armature 2, and it can be used to energize the magnet poles. The latter are stationary.

The function of the arrangement is as follows: The 50 auxiliary dynamo is used to increase the momentum of the motor, while the fan 16 absorbs part of the energy of the dynamo gear. Both elements combine their effect, when conditions are properly selected, perfectly to balance the difference of energy caused 55 by the loss of electric current caused by the transmission of the same from the dynamo to the motor.

A third example to avoid the injurious difference of power consists in connecting a fan 16 to that part of the dynamo which is magnetically coupled by reaction 60 and which is connected with the drive wheel, which

part consists in the example shown of the field magnets of the dynamo. Said fan regulates the course of both driving elements in such a way, that, in starting, the full power is transmitted to the wheels, while at increased speed the difference of the power of the dynamo 70 and the electromotor is balanced by the energy required for rotating the fan. The dimensions of the fan are such, that, at full speed, the torque of both driving elements is balanced, whereby both wheels are uniformly rotated. The arrangement described has a 75 further advantage in a constant current of air passing through the casing of the apparatus, whereby the latter is satisfactorily cooled.

In a further example of the invention, shown in Fig. 5, the dynamo-electric gear explained with reference 80 to Figs. 1-4, in which the armature as well as the magnet poles are arranged to rotate, is substituted by a dynamo one part of which, either the armature or the poles, is stationary, the rotating element being connected, through an intermediate differential gearing, 85 with the driving shaft as well, as with the driven shaft. In the example shown, power can be transmitted from the shaft 1 actuated by any desired source of energy through bevel gears 17, 18, 19, 20 and 21 to the magnet poles 8, 8 exerting a torque on the armature of the 90 dynamo gear. The bevel gears 20, one of which may evidently be dispensed with, are mounted in such a way as to be capable of a rotation with the shaft 23 a part of a rotation about the pivot 22. To the shaft 23 the driving element 24 is coupled which transmits motion 95 for example to the back wheel. The function of this example of the invention is as follows: As long as the shaft 23 does not rotate and current is not taken from the dynamo-gear 2, 8, the magnet poles 8, or the armature 2 as the case may be, rotate without any load and 100 no torque is exerted on the shaft 23. As soon, however, as the dynamo-electric gear is charged by being electrically connected with the motor, the bevel gear 20 begins to roll on the bevel gear 21 and to transmit a torque to the shaft 23, according to the amount of current produced. Simultaneously, however, the motor 6, 7 will transmit a momentum to the shaft 24, according to the current supplied, whereby by means of the driving wheel 25 the second carriage wheel is operated independently of the other carriage wheel. 110 Also in this example the mechanism may be included within a casing 11. Instead of the magnet poles the armature may, under certain circumstances, advantageously be directly coupled with the bevel gear 21, in which case the magnet poles 8, 8 are stationary. 115

I claim:

1. In a dynamo-electric variable speed gearing, the combination with a prime mover of a dynamo electric gear comprising a field element and an armature element adapted to be rotated relatively to each other by said prime mover, means operatively connected with one of said elements and adapted to be rotated by the reaction exerted by said elements on each other, an electrical motor having a movable member adapted to turn about the same axis as the dynamo electric gear, a circuit including the armature windings of said motor and of said dynamo electric gear, and means adapted to be rotated by said motor.

2. In a variable speed gearing, the combination with two elements adapted to turn about a common axis, of a prime mover, a dynamo comprising a field member and an armature adapted to be rotated relative to each other by the prime mover, means connecting one of said members of the dynamo with one of said elements, an electric motor, means

connecting a rotary member of said motor with the other of said elements, and an electric circuit including the armatures of said motor and dynamo.

3. In a dynamo-electric variable speed gearing, the combination, with a prime mover, of a dynamo electric gear comprising a field element and an armature element adapted to be rotated relatively to each other by said prime mover, means operatively connected with one of said elements and adapted to be rotated by the reaction exerted by said elements on each other, an electrical motor, a circuit including the armature windings of said motor and of said dynamo electric gear, means to vary the magnetic fields of said dynamo electric gear and of said motor, and means adapted to be rotated by said motor.
- 10 4. In a dynamo-electric variable speed gearing, the combination, with a prime mover, of a dynamo electric gear comprising a field element and an armature element adapted to be rotated relatively to each other by said prime mover, means operatively connected with one of said elements and adapted to be rotated by the reaction exerted by said elements on each other, an electrical motor, a circuit including the armature windings of said motor and of said dynamo electric gear, means adapted to be rotated by said motor, and means adapted to be rotated by said motor.
- 15 5. In a dynamo-electric variable speed gearing, the combination, with a prime mover, of a dynamo electric gear comprising a field element and an armature element adapted to be rotated relatively to each other by said prime mover, means operatively connected with one of said elements and adapted to be rotated by the reaction exerted by said elements on each other, an electrical motor, a circuit including the armature windings of said motor and of said dynamo electric gear, means adapted to be rotated by said motor, and means to balance the power exerted by said motor.
- 20

circuit including the armature windings of said motor and of said dynamo electric gear, means to vary the magnetic fields of said dynamo electric gear and of said motor, and means adapted to be rotated by said motor.

25

6. In a dynamo-electric variable speed gearing, the combination, with a prime-mover, of a dynamo electric gear comprising a field element and an armature element adapted to be rotated relatively to each other by said prime-mover, means operatively connected with one of said elements and adapted to be rotated by the reaction exerted by said elements on each other, an electrical motor, a circuit including the armature windings of said motor and of said dynamo electric gear, means adapted to be rotated by said motor, and means to balance the power exerted by said motor.
